ELEVATOR LOCK

Harold A. Flint, San Francisco, and Charles F. Lantz, Oakland, Calif.

Application July 5, 1949, Serial No. 103,084

3 Claims. (Cl. 187—31)

1

This invention relates to elevator locks for use in connection with elevator gates or doors to prevent movement of the elevator when the gate or door is open and to prevent the opening of the gate or door except when the elevator is present at the floor. The invention is similar to that disclosed in our copending application for patent Serial No. 777,978, filed October 4, 1947, Patent No. 2,499,481, issued March 7, 1950.

Prior devices of this nature have for the most part been relatively complicated and expensive to make and have many times required expensive accurate machining operations. These previous devices have generally employed a means actuated by the elevator for engaging or disengaging a gate latch which in turn either locks or unlocks the elevator gate, thus establishing an interdependence between the elevator actuated means and the gate latch. Also the means for making and breaking the power circuit has generally been made dependent upon the means actuated by the gate.

One of the objects of this invention is the provision of an elevator lock which is extremely simple to make and to maintain.

Another object of the invention is the provision of an elevator lock which obviates the accurate machining operations required in locks having various interengaging parts.

Generally stated, the present invention contemplates the provision of an elevator lock which employs two independent latches, one for engaging and locking the gate in closed position and another for breaking the elevator power circuit. The independence of these latches makes for a less expensive construction and reduces the number of parts required.

Other objects and advantages of the present invention will be seen from the following specification and the attached drawings wherein:

Fig. 1 is a front elevational view of the locking mechanism with the housing cover removed.

Fig. 2 is a side elevational view partly in section of the mechanism shown in Fig. 1 but with the upper latch omitted for clarity and as taken along lines 2—2 of that figure.

Fig. 3 is a side elevational view similar to Fig. 2 but as taken along the lines 3—3 of Fig. 1.

Fig. 4 is a fragmentary assembly view of the invention shown in conjunction with an elevator and an elevator gate.

Fig. 5 is a fragmentary plan view of the invention shown in conjunction with an elevator and an elevator gate.

Referring to Figs. 1 and 2, the invention is pro-

2

vided with a box-like housing generally designated 1 and having a pair of opposed side walls 2, 3 a bottom wall 4 and a back wall 5. The top and front of the housing are open but are adapted to be covered by a removable cover plate (not shown). Spaced from the back wall 5 is a mounting plate 6 which is parallel to the back wall 5 but spaced therefrom by a spacer 7 adjacent the lower edge of the back wall 5.

The back wall 5, mounting plate 6 and the spacer 7 may be integrally cast together as shown in Fig. 2 but however formed, the spacing between the backwall 5 and the mounting plate 6 results in a relatively narrow upwardly and laterally outwardly opening slot 8 extending the greater part of the vertical length of the back plate 5.

Extending between sidewalls 2, 3 adjacent their upper ends and journaled therein is a shaft 10 which extends laterally outwardly of the sidewall 3 and to which is secured an arm 11 by means of clamping bolt 12. The arm 11 extends radially outwardly of the shaft 10 and is provided at its outer end with a roller 13 for a purpose to be subsequently described in detail. Secured to the shaft 10 intermediate the walls 2, 3 is a latch member 15. This latch member 15 is adjustably secured to shaft 10 by means of set screw 16 and may be angularly positioned relative to the arm 11 as desired. A pair of spacers 17, 18 (Fig. 1) may be provided on shaft 10 between the latch 15 and walls 2, 3 respectively to prevent axial movement of the shaft 10 relative to the housing 1.

As best seen in Fig. 3, the latch 15 which is preferably cut from relatively heavy gage steel is formed with a tooth 20 and has a relatively straight lower face 21 and a curved, cam-like upper surface 22 for a purpose to be subsequently described in detail. When the latch 15 is swung to the full line position of Fig. 3 this tooth 20 extends through an opening 23 in backplate 5 and which opening is formed so that its upper edge 24 acts as a stop to prevent further movement of the latch 15 to the right as seen in Fig. 3. A corresponding opening 26 is formed in the mounting plate 6 to permit clearance for the tooth 20.

Another shaft 30 extending between sidewalls 2, 3 and spaced downwardly therefrom supports another latch 31 which is rotatable on said shaft (Fig. 1). Spacers 32, 33 space the latch 31 from the sidewalls 2 and 3 to permit the latch 31 to clear the latch 15.

As best seen in Fig. 2, the latch 31 which is

also preferably formed from heavy gage steel is generally triangular in shape and is provided with a pair of generally vertically spaced projections 34, 35 for a purpose to be subsequently described. Secured to the side of the catch 31 and positioned adjacent the corner of latch 31 opposite the projections 34, 35 is a pin 36. This pin 36 pivotally supports the upper end of a vertically disposed switch arm 37 which carries adjacent its lower end a jumper 38. This jumper 38 is provided with a pair of contacts 39, 40 adapted to engage power circuit connections 45, 46 upon upward movement of the arm 37. In Figs. 1 and 2 the switch is shown in full line in its closed position and in dotted line in its open position. In the latter position, the power line of the elevator is broken and the elevator cannot be moved. The lower end of the arm 37 is reduced in cross-section as at 47 and the jumper 38 is slidable along this reduced portion but is urged upwardly by a spring 48 surrounding the reduced portion of the arm 37 and bears at its lower end against a plate 49 secured to the end of the arm 37. The spring 48 permits overtravel of the arm 37 when the same moves upwardly under the action of the latch 31.

In the full line position of latch 31 in Fig. 2, the jumper 38 completes the circuit to the elevator. Referring to Fig. 2 it is seen that the lower projection 35 of the latch 31 is being held to the left by a member 51 which member is the lower extremity of an arm generally designated 52 (Figs. 4 and 5) secured to the elevator gate 53. Thus when the gate is closed, the member 51 engages the latch 31 at its lower projection 35, closing the power circuit to the elevator. An opening 57 in backplate 5 is provided to permit the projection 35 to enter the slot 8 and an opening 61 is provided in mounting plate 6 to permit free movement of the projection 35 through the backplate. As can be seen from Fig. 2, upon upward movement of the member 51, when the gate is opened, the member 51 will engage the upper projection 34 of the latch 31 rotating the latch counter-clockwise and positively breaking the contacts 39, 45 and 40, 46 to prevent movement of the elevator. An extension 27 of back-wall 5 is provided slanting generally upwardly and away from mounting plate 6 to facilitate the entrance of member 51 into the slot 8.

Referring to Fig. 4 the roller 13 on the arm 11 is adapted to engage a "shoe" 55 secured to the elevator 56 so that when the elevator approaches the floor level, whether it is moving upwardly or downwardly, the arm 11 will be swung into the full line position of Fig. 4, thus swinging the latch 15 clockwise to cause the tooth 20 to move out of the slot 8 and into the housing 1 and permitting upward movement of the member 51 upon opening of the gate 53. Thus it is seen that when the elevator is not adjacent the floor, the member 51 is held against upward movement by the tooth 20 on the latch 15. Upon approaching the floor, the elevator causes the arm 13 to swing clockwise as seen in Fig. 4 to swing the latch 15 out of the slot 8 thus permitting opening of the gate 53. In Fig. 2 the arm 11 is shown formed in two sections 62, 63, which are slidable with respect to each other. Elongated slot 64 formed in section 63 and bolt 65 threadedly secured to section 62 permit longitudinal adjustment of the arm 11 for properly positioning the same with respect to shoe 55.

The latch 15 may be weighted as shown in Fig. 3 to cause the tooth 20 to be urged into the slot 8, however, it is preferable that a torsion spring

such as is indicated at 19 in Fig. 1 be also provided on the shaft 10 for positively urging the tooth 20 into the slot.

It is apparent that the present invention provides a simple and inexpensive safety device for use with elevators. It is to be understood that the device herein disclosed is merely a preferred embodiment of the invention and modifications may be made thereto without departing from the spirit of the invention.

We claim:

1. A lock for a motor actuated elevator and for a shaft gate comprising, a body adapted to be stationarily secured to a wall of an elevator shaft adjacent an entrance to such shaft and provided with a vertically extending upwardly opening passageway for vertically reciprocable movement of a member on said gate into and out of said passageway through its open upper end, a first latch and a second latch respectively supported on said body for movement to and from a position extending across said slot with said first latch positioned above said second latch, an element connected with said first latch engageable by said elevator upon movement of the latter to said entrance for causing said movement of said first latch out of said passageway to permit passage of said gate member therewith and out of said passageway, said second latch including a projection engageable by said gate member upon movement of the latter into said slot and past said first latch for moving said second latch across said passageway and over said member, a pair of electrical contacts on said body respectively in an electrical circuit with the elevator motor, a switch bar for said contacts and closing said circuit connected with said second latch for movement to circuit closing position upon movement of said second latch to said position over said member and for movement to circuit opening position upon movement of said second latch out of said passageway.

2. A lock for a motor operated elevator and for a vertically reciprocable shaft gate at a landing in the shaft in which said elevator is movable comprising, a body adapted to be stationarily secured to a wall of said shaft at said landing and in a position for receiving a member on said gate when the latter is closed and at the lower end of its stroke, said body being provided with a pair of spaced, vertically disposed walls between which said member is adapted to be so received, an upper pair and a lower pair of horizontally aligned openings formed in two opposite sides of said passageway, a latch, formed with a pair of vertically spaced laterally extending projections, respectively adjacent said upper and said lower pairs of openings, a pivot between said projections and to one side of a line extending between said projections supporting said latch on said body for swinging the upper and lower projection into and out of said upper and said lower pairs of openings upon oscillation of said latch on said pivot under the influence of said member upon said gate being closed and opened, said upper projection being disposed over said member and through said upper pair of openings upon said gate being closed, an electrical circuit in which the elevator motor is disposed, a mechanical switch on said body and in said circuit, a link connecting said switch with said latch for opening said switch upon movement of said upper projections out of said openings under the influence of said member when said gate is opened, and for closing said

switch upon movement of said upper projection into said openings when said gate is closed.

3. A lock for a motor operated elevator and for a vertically reciprocable shaft gate at a landing in the shaft in which said elevator is movable comprising, a body adapted to be stationarily secured to a wall of said shaft at said landing, said body being formed with an upwardly and outwardly opening passageway adapted to receive therein a member on such gate when said gate is closed and at the lower end of its stroke, a first latch pivotally supported on said member for movement to a position extending across said passageway and said member when said gate is closed, a cam actuated follower connected with 10 said first latch for causing withdrawal of said first latch when said elevator is at said landing,

5 and a cam engageable by said follower for so actuating said first latch, an electrical circuit for the motor elevator, a mechanical spring actuated switch in said circuit and on said body for normally holding said switch open and a second catch pivotally supported on said body and connected with said switch for closing the latter upon movement of said latch under the influence of said member when said gate is closed, said second latch including a projection thereon engageable by said member when said gate is closed for so moving said second latch.
